UNITED STATES PATENT OFFICE.

LEROY C. HAYES, OF DECATUR, ILLINOIS.

DESIGN FOR A CARPET-CLEANER CYLINDER.

SPECIFICATION forming part of Design No. 30,617, dated April 25, 1899.

Application filed February 23, 1898. Serial No. 671,391. Term of patent 7 years.

To all whom it may concern:

Be it known that I, LEROY C. HAYES, of the city of Decatur, county of Macon, and State of Illinois, have invented and produced a certain new and useful Design for Carpet-Cleaning Cylinders, of which the following is a specification.

The design is exemplified in the structure shown in the drawings forming part of this specification. It relates to the shape or configuration of the cylinder and it has peculiarities as follows: The ends of the cylinder have the appearance delineated in Figure 1 of the drawings, which is an end elevation. The extreme perimeter of the cylinder is defined by a circle, as 1. Bars, as 2, radiate from the axis 8 of the cylinder to perimeter 1 and divide the circle into four equal parts, while bars, as 3, radiate from the axis to the perimeter and subdivide each of the divisions made by bars 2 into three substantially equal parts. Parallel bars extend from one end of the cylinder to the other, as shown in plan in Fig. 2, and they are disposed with relation to

substantially as shown in Fig. 1—that is to say, they coincide with the circle and form arcs thereof, as shown at 4, for distances extending beyond each bar of each adjoining pair of bars 3, and from the ends of the arcs they diverge inward in right lines, as shown at 5, and meet on bars 2. The circular outlines are defined by a plurality of bands, as 1 and 1^a, distributed along the perimeter of the cylinder with the broadest one in the center. A square, 35 as 6, is formed at each end of the frame by bars that meet on radial bars 2 inside the figure described by the parallel bars, and bars, as 7, are disposed inside such figure outside the square and parallel with the sides thereof. 40

What I claim is—

The design for a carpet-cleaner cylinder herein shown and described.

In testimony whereof I sign my name in the presence of two subscribing witnesses.

LEROY C. HAYES.
